UNITED STATES PATENT OFFICE.

HENRY CUTTING, OF BUFFALO, NEW YORK, ASSIGNOR OF ONE-HALF TO
THOMAS J. DE LANEY, OF SAME PLACE.

SASH-HOLDER.

SPECIFICATION forming part of Letters Patent No. 291,697, dated January 8, 1884.

Application filed October 2, 1883. (No model.)

To all whom it may concern:

Be it known that I, HENRY CUTTING, of the city of Buffalo, in the county of Erie and State of New York, have invented a new and useful 5 Improvement in Sash-Holders, of which the following is a specification.

This invention relates to an improvement in that class of sash-holders which consists, essentially, of a screw-bolt working in a threaded opening or screw-nut in the sash, and provided with a bearing-piece adapted to be pressed against the window frame or casing by turning the screw-bolt, thereby locking the sash in position.

15 The object of my invention is to produce a sash-holder of this character in which the requisite longitudinal movement of the clamping-piece is effected very rapidly and without making the screw-thread so steep that its holding-power will be impaired.

20 My invention consists, to these ends, of the improvement in the construction of the sash-holder, which will be hereinafter fully set forth, and pointed out in the claims.

25 In the accompanying drawings, Figure 1 represents a sectional elevation of my improved sash-holder. Fig. 2 is a cross-section in line *x x*, Fig. 1. Fig. 3 is an end view of the screw-nut and bearing-piece. Fig. 4 is a longitudinal section of the bearing-piece. Fig. 5 is a similar view of the screw-nut. Fig. 6 is a sectional elevation, showing my improved sash-holder applied to the window of a railway-car. Fig. 7 is an elevation of this sash-holder. Fig. 8 is a cross-section in line *y y*, Fig. 7.

30 Like letters of reference refer to like parts in the several figures.

A represents a portion of the window casing or frame, and B a portion of the side piece of the sash. C represents the screw-bolt of the sash-holder, and D the screw-nut secured in the sash. The screw-nut D is made cylindrical on its exterior surface and seated in a cylindrical recess formed in the edge of the sash, in which it is prevented from turning by longitudinal tapering ribs *d*, which are formed on the outer surface of the screw-nut, and embed themselves in the wood as the screw-nut is driven into the recess.

e represents the internal screw-thread formed 5c in the inner or rear portion of the screw-nut.

f represents a cylindrical cavity formed in the outer or front portion of the screw-nut.

G represents the bearing-piece arranged in the cavity *f*, so as to slide therein toward or 55 from the window-casing A, and provided with an internal screw-thread, *h*. The screw-bolt C is constructed with two threaded portions, *i* and *j*, which engage, respectively, in the internal screw-threads, *e* and *h*, of the screw-nut 60 D and bearing-piece G. The screw-threads in the screw-nut D and bearing-piece G are arranged in opposite directions, the threads *e* and *i* being represented as left-hand threads and the threads *h* and *j* as right-hand threads. The 65 bearing-piece G is guided in the recess *f* by a longitudinal rib, *k*, formed on the outside of the bearing-piece and projecting into a longitudinal groove, *l*, formed in the inner wall of the recess, whereby the bearing-piece G is prevented from turning, but permitted to move lengthwise in the recess of the screw-nut. Upon 70 turning the screw-bolt C in one or the other direction a quick axial movement is imparted to the bearing-piece G, proportionate to the 75 pitch of the two screw-threads, and the bearing-piece is rapidly pressed against the window-frame to lock the sash, or removed therefrom to release the sash, as may be desired. The desired quick movement of the bearing-piece is attained without making the screw-threads so steep as to impair their holding-power.

In the construction represented in Figs. 6, 7, and 8 the screw-nut D is secured to the surface of the sash by flanges *m* and screws *n*, and the bearing-piece G is constructed in the form of a dovetail and guided in a dovetail recess in the screw-nut. The bearing-piece is provided at its outer end with a projection or 90 stud, *o*, which is adapted to engage over projections *p*, secured to the window-casing. This construction is especially designed for use on the windows of railway-cars, which cannot be securely locked in position merely by the friction of the bearing-piece G against the side of the window-casing. The screw-threads are 95 preferably made so steep that half a turn of the

fastening-bolt will be sufficient to fasten or release the sash, and the parts are preferably so arranged that the weighted handle *q* of the screw-bolt will depend in the position represented in Fig. 6 when the bearing-piece is projected.

The several parts of my improved sash-holder are readily cast complete of iron or other suitable metal and put together without requiring any fitting, and the device is therefore produced at comparatively small expense.

I claim as my invention—

1. In a sash-holder, the combination, with a screw-bolt having a right-hand and a left-hand screw-thread, of a fixed screw-nut receiving one of said screw-threads, and a movable bearing-piece working on the other screw-thread, substantially as set forth.

2. The combination, with a screw-bolt, *C*, provided with a right-hand and a left-hand screw-thread, of a screw-nut, *D*, provided with a screw-thread, *e*, and a cavity, *f*, and a bearing-piece, *G*, provided with a screw-thread, *h*, and guided in the cavity *f*, substantially as set forth. 25

3. The combination, with a screw-bolt, *C*, having right and left hand screw-threads *i* and *j*, of a fixed nut, *D*, having a screw-thread, *e*, a recess, *f*, and a longitudinal groove, *l*, and a bearing-piece, *G*, constructed with a screw-thread, *h*, and rib *k*, and arranged in the recess *f*, substantially as set forth. 30

HENRY CUTTING.
